UNITED STATES PATENT OFFICE

HAROLD O. BERRY AND FRED E. WHITE, OF GARDNER, MASSACHUSETTS, ASSIGNEES
TO FLORENCE STOVE COMPANY, OF GARDNER, MASSACHUSETTS, A CORPORATION OF
MASSACHUSETTS

DESIGN FOR A COMBINED LIQUID FUEL RESERVOIR AND BOWL

Application filed September 8, 1932. Serial No. 44,782. Term of patent 7 years.

To all whom it may concern:

Be it known that we, HAROLD O. BERRY and FRED E. WHITE, citizens of the United States, residing at Gardner, in the county of Worcester, and State of Massachusetts, have invented a new, original, and ornamental Design for a Combined Liquid Fuel Reservoir and Bowl, of which the following is a specification, reference being had to the accompanying drawing, forming part hereof.

The figure is a perspective view of a combined liquid fuel reservoir and bowl embodying our design.

We claim:

The ornamental design for a combined liquid fuel reservoir and bowl, substantially as shown.

HAROLD O. BERRY.
FRED E. WHITE.
